UNITED STATES PATENT OFFICE.

EVA EICKEMEYER ROWLAND, OF YONKERS, NEW YORK.

FELTED HEAD WEAR.

SPECIFICATION forming part of Letters Patent No. 554,378, dated February 11, 1896.

Application filed October 7, 1893. Serial No. 487,486. (No model.)

To all whom it may concern:

Be it known that I, EVA EICKEMEYER ROWLAND, of Yonkers, in the county of Westchester and State of New York, have invented 5 certain new and useful Improvements in Felted Head Wear for Ladies, Misses, and Children; and I do hereby declare that the following specification, taken in connection with the drawings furnished and forming a part of the 10 same, is a clear, true, and complete description of my invention.

The objects of my invention are to provide a comparatively inexpensive and serviceable line of fall and winter hats, bonnets, or hoods 15 in various forms, styles, or designs and to enable the same to be economically produced or developed from soft-felted hat-bodies by providing each body with certain guiding media for enabling comparatively unskilled persons 20 to readily develop such hat-body into a hat having a predetermined form, style, or design, and, further, in some cases to enable a single hat-body to be readily developed into a hat in any one of several predetermined forms, 25 each in fact constituting a separate and distinct style or design.

The advantages of my invention will be available not only to persons who may purchase such goods for their own or their children's use, but also to manufacturers, whether 30 they send to market the hat-bodies or the hats trimmed or untrimmed, because in either case the guiding media, in accordance with my invention, assure prompt and ready development 35 of the hat-bodies into intended predetermined forms, styles, or designs at the hands of comparatively unskilled persons.

To the ends recited the main feature of my invention consists in a hat-body having variously-located guide-marks in pairs, series 40 or groups, so that when any one guide-mark, as by folding or pinching the felt together, is made to register with one or more of the marks in its own pair or group and a union 45 of the felt made at that point, at least one element in the intended form or design will have been secured, and also so that when the guide-marks of each pair or group are thus registered and the folded felt tied or united 50 at the several points the hat-body will have been developed in the style or design predetermined by the several guide-marks.

Another feature of my invention consists in a hat-body having different sets of the said folding guide-marks, so that one hat-body 55 may be developed into either of the styles or forms of hat which may have been predetermined by the guide-marks—as, for instance, so that a hat-body by way of one of its sets of guide-marks could be developed into a hat 60 suitable for use by a mother and which after awhile, by way of another set of guide-marks, could be readily converted into a form or style of hat only suitable for a child, it being practicable to thus provide for developing 65 several distinct styles of hat from the one hat-body.

Inasmuch as the gist of the main feature of my invention will be embodied in a hat-body having suitable guide-marks in groups, or series, or pairs, for so guiding the operations of folding or pinching and uniting the felt as to assure a predetermined form of hat, it will be obviously immaterial in what manner or form said guide-marks may be produced so 75 long as they serve the purposes indicated. Said marks may be merely spots of color contrasting with the color of the hat-body, but with a view to the ready, convenient, and economical formation of hats. Another feature of my invention consists in a hat-body 80 having perforated guide-marks, so that when the appropriate perforations have been made to register with each other, the union of the felt can be at once effected by the use of any 85 suitable tying medium, preferably of the well-known paper-fastener types. In places where the fasteners can be concealed ordinary metallic fasteners may be used, but specially-adapted fasteners will often be desirable, the 90 same having either plain or ornamental heads, and in some cases the heads may be in part composed of felt cut or folded in symmetrical forms. The character of the perforated guide-marks may also be widely varied—as, for instance, they may be small holes, as cut by a punch, either round, square, or triangular, or they may be straight or curved, or cross-slits 95 in the felt, in either case providing for the ready application of a tying medium, whether of the paper-fastener variety or twine or ribbon, the latter, in some cases, being specially desirable. The slotted perforations, although discernible as guide-marks, will, when not in 100

actual use, be so closed as to obviate defacing the hat, although generally any unused guide-marks can be well covered by the usual trimming, and, if not, they can be occupied by a 5 fastener having an ornamental head, or a felt rosette.

It will obviously be quite impracticable to herein describe, or to illustrate in the drawings, the numerous desirable transformations 10 of hat-bodies into hats, which I have thus far conceived of, in accordance with my invention. This specification will therefore be restricted to a description of three transformations, which will no doubt enable persons 15 skilled in such matters to fully comprehend my invention, and to not only practice the same on the lines specially indicated, but also enable them to readily enlarge thereon in various directions as to matters of form and design, 20 without any substantial departure from the spirit of my invention.

Referring to the drawings, Figure 1 illustrates, in separate views, opposite sides of a flattened hat-body with the front and rear lines located at the edges, as indicated. Fig. 2 in like manner illustrates the same hat-body oppositely flattened, the front and rear portions being clearly indicated, these figures illustrating the use on one hat-body of 25 three sets of guide-marks for enabling it to be readily developed into a hat in either of three separate predetermined forms or designs. Fig. 3, in front and side views, illustrates one of said designs, the other two being similarly illustrated in Figs. 4 and 5. Fig. 30 6 illustrates a piece of felt provided with various kinds or forms of guide-marks; and Figs. 7 to 10, inclusive, illustrate various forms of tying or fastening devices, each in 35 side and top views.

It is well known that felted hat-bodies are normally in conical form, as shown at A, Figs. 1 and 2, and it is in this form that I prefer to use them, because in most cases it is 40 desirable to retain the conical tip, and also with a view to economy in avoiding the cost of stretching and blocking, and, although an unstretched and unblocked or conical hat-body embodying my improvement constitutes 45 a novel and valuable feature of my invention, I do not restrict my invention thereto, inasmuch as variations in the form of a hat-body, as by stretching or blocking, or both, would involve no departure from the main 50 feature of my invention, it being obvious that one such variation will be at times specially desirable—as, for instance, in the development of a rudimentary brim, or an unequal or irregular enlargement at the tip, at 55 front or rear; or further, in the formation of bulbous enlargements at one or more points upon the side crown.

Hat-bodies, as ordinarily produced in the manufacture of men's hats, are well suited 60 for my purposes, although, as little or no stretching or blocking is required, the bodies can be lighter in weight than usual. Although

pounced surfaces are generally desirable, the bodies are sometimes fleeced or napped in whole or in part, and sometimes left unpounced, and for specially rustic styles the bodies should retain the hair, which is ordinarily pulled from the felt.

Now referring to Figs. 1 and 2 it is to be understood that the four views disclose three 70 sets of folding guide-marks, designated $b b'$ b^2 , and so on through the b series, $c c' c^2$, and so on through the c series, and $d d' d^2$, &c., through the d series; but some of the marks perform duty in more than one set.

Next referring to the woman's hat B, (shown in front and side views in Fig. 3,) it will be seen that this design can be and is readily developed from the conical form by using the guide-marks of the b series, of which the marks b , b' , b^2 , and b^3 are on the front line and the marks b^4 and b^5 on the rear line. In this instance all of the front-line group of guide-marks are made to register by folding the felt into four thicknesses, as indicated, it then 90 being only necessary to apply the tying or fastening medium, which in this instance is a metallic fastener provided with a star-shaped ornament, which may be composed of felt, either of the same color as the hat-body or 95 contrasting therewith, if desired. The rear portion of this hat is developed by registering the guide-marks b^4 and b^5 and applying a fastener which secures the upward fold in position, the rear and front folds thus formed 100 causing at the sides of the hat a rounded line, beneath which the felt inclines downwardly and inwardly in symmetrical form.

Now, referring to the child's hat C, (shown in side and front views in Fig. 4,) it will be seen 105 that its design involves a radical departure from the lines of the hat Fig. 3, although developed from the same body. In this case the central front portion of the body is pinched or folded inwardly and the guide-marks b^2 110 and b^3 made to register with each other, a fastener being then applied inside of the hat. A rear upward fold is also made, so as to cause the guide-mark c to register with c' , and the mark c^2 with c^3 , fasteners being then applied, 115 thus securing the felt in position at the two sides of the hat near its lower edge, said fasteners having rosette heads. It will be seen that the front upper line of this hat can be 120 readily varied without departing from the design—as, for instance, for increasing the height of the cone and lessening the front or brim the guide-marks b' and b^2 should be registered with each other.

Next referring to the child's hat or hood D, 125 Fig. 5, it will be seen that a still more radical variation in form or design is involved, which requires certain additional guide-marks of the d series, although therewith some of the b and c series are employed. The pair of 130 guide-marks $d d'$, located near the front line, but on each side thereof, when registered with each other with the felt pinched inwardly, secures a symmetrical fold located at the top of

the hat, extending rearwardly. The tip of the cone is inclined forwardly and downwardly by pinching the felt inwardly and causing the guide-mark d^2 to register with the mark b^3 , and on having a fastener applied symmetrical bends are secured at each side of the point of union, as indicated. A front rearward fold is assured by registering and fastening the guide-marks d^3 and d^4 at one side and at d^5 d^6 on the other side, these being similar to and near the guide-marks c c' and c^2 c^3 , which in this case, as before, do duty in securing the upward rear fold of the felt.

Vertical folds at the sides and rear of the hat are desirable, and these are formed by pinching the felt inwardly, causing the marks d^7 d^8 and d^9 d^{10} to be registered in pairs, and applying fasteners as described.

It will be obvious that my invention extends to and includes any arrangement of guide-marks by means of which any one particular form of hat can be predetermined, and so that an unskilled person may readily follow said marks and produce the intended hat, and this, too, whether a hat-body be provided with one, two, or more sets of guide-marks. It will also be obvious, as indicated by dotted lines in Figs. 4 and 5, that when a hat-body is provided with only a single set of guide-marks the details of any given design may be quite largely varied from the details of the same general design when provided for by one of several sets of guide-marks on the same hat-body.

Whether one or more sets of marks are applied to one body they can be readily located and applied by the use either of a flat perforated templet, as on a flatly-folded body, or by a conical templet, as when the hat-body is supported on a conical block. These templets being either of wood, paper, or metal, and appropriately perforated, will serve as stencils when color is used, or as gages for the use of punches or slitting-cutters in producing perforated guide-marks.

Referring now to Fig. 6, a piece of felt A' is shown provided with a variety of guide-marks, that at e being a circular spot of color.

The mark e' is a circular hole, as from an ordinary punch. Mark e^2 is a short straight cut or slit in the felt. Mark e^3 is a curved slit, and the mark e^4 is a cross-cut or double slit. Either or all of these guide-marks may be employed advantageously on one hat-body. All of the slitted forms, when not actually used, will scarcely be noticeable in the hat, and need not be covered by trimming or occupied by an ornamental fastener, as is usually desirable with the unused marks e' . For clearly pairing those marks which are to register with each other they may be alike, the several pairs or groups being different from each other.

As hereinbefore indicated, securing devices of the paper-fastener type will generally be desired, whether the guide-marks be perforated or not. The ordinary T-shaped fastener is shown in Fig. 7 and the round-head fastener in Fig. 8.

The requirement in some cases for specially ornamental effects will be met by the use of a fastener provided with a rosette-head, as shown in Fig. 9, or by the use of felt in fanciful forms, one of which is illustrated in Fig. 10, wherein a star composed of felt constitutes a part of the head of the fastener.

Having thus described my invention, I claim as new, and desire to secure by Letters Patent—

1. A felted hat-body having a set of guide-marks, in several pairs or groups, substantially as hereinbefore described, for enabling one of several predetermined forms or styles of hat to be formed, by causing appropriate guide-marks to register with each other and uniting the felt at said registered marks.

2. A felted hat-body having perforated guide-marks in groups or pairs, substantially as hereinbefore described, whereby on registering appropriate perforations with each other, and applying a fastening device, a predetermined form of hat may be readily and economically produced.

EVA EICKEMEYER ROWLAND.
